UNITED STATES PATENT OFFICE

108,139

DESIGN FOR A RIBBON

John D. Huizing, New York, N. Y.

Application December 20, 1937, Serial No. 73,732

Term of patent 7 years

To all whom it may concern:

Be it known that I, John D. Huizing, a citizen of the United States of America, residing in New York city, in the Borough of Manhattan, county and State of New York, have invented a new, original, and ornamental Design for a Ribbon, of which the following is a specification, reference being had to the accompanying drawing, forming part thereof, wherein,

The figure is a plan view of a piece of ribbon showing my new design.

I claim:

The ornamental design for a ribbon, substantially as shown.

JOHN D. HUIZING.
